UNITED STATES PATENT OFFICE.

VINCENT M. HAAS, OF NORRISTOWN, PENNSYLVANIA, ASSIGNOR TO PYRAMID FIRE GRATE COMPANY, INC., OF NORRISTOWN, PENNSYLVANIA, A CORPORATION OF DELAWARE.

GRATE FOR STOVES AND FURNACES.

1,121,180.

Specification of Letters Patent. Patented Dec. 15, 1914.

Application filed February 13, 1913. Serial No. 748,265.

To all whom it may concern:

Be it known that I, VINCENT M. HAAS, a citizen of the United States, residing at Norristown, in the county of Montgomery and State of Pennsylvania, have invented a new and useful Grate for Stoves and Furnaces, of which the following is a specification.

The invention relates to improvements in grates.

The object of the present invention is to improve the construction of grates, and to provide a simple, inexpensive and efficient rotary roller bearing shaking grate, designed for use in stoves and in the furnaces of hot air steam and hot water heating systems, and equipped with means for reducing the area of the fire pot without lessening the size or capacity of the ring or wall of fire, which impinges against the interior of the casing of the stove or furnace, whereby the fire will be most advantageously placed for the distribution of heat, and practically the same heating effect will be obtained as with a fire pot of increased capacity and at the expenditure of a smaller amount of fuel.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a vertical sectional view of a portion of a furnace equipped with a grate, constructed in accordance with this invention. Fig. 2 is a horizontal sectional view of the same. Fig. 3 is a plan view of the rotary shaking ring or annular grate member. Fig. 4 is a plan view of the central section and support of the grate. Fig. 5 is a detail view of a portion of the fire pot cylinder. Fig. 6 is a detail sectional view, illustrating another form of the fire spreading cone. Fig. 7 is a detail sectional view on the line 7—7 of Fig. 2.

Like numerals of reference designate corresponding parts in all the figures of the drawings.

In the accompanying drawings in which is illustrated the preferred embodiment of the invention, the grate comprises in its construction a support consisting preferably of a casting and composed of a central circular grate section 1 and integral radial supporting arms 2, connected at their inner ends with the central grate section at the periphery thereof and extending outwardly therefrom to the casing 3 of a furnace 4 and secured to an inwardly extending annular supporting flange 5 of a base 6 of the furnace by bolts 7, which pierce the ends of the arms 2 and the flange 5. The grate may, however, be applied to an ordinary heating stove, or to any other form of furnace, and the central grate section 1 is provided with a depending flange 8, and it has an annular series of spaced projections 9 forming intervening recesses 10 and arranged in flush relation with the upper face of the central grate section 1. The depending annular flange 8 downwardly offsets the radial supporting arms 2 from the plane of the upper face of the central grate section 1, and enables a rotary shaking ring 11, which is supported by the arms to be arranged in flush relation with the central grate section 1.

The rotary shaking ring constitutes an annular grate member and is provided at its inner and outer edges with spaced projections 12 and 13, forming intervening recesses 14 and 15, and it surrounds the central grate section 1 and is located in the space between the same and a fire pot cylinder 16. The ring is also provided between its inner and outer edges with curved slots 15^a spaced from each other and separated by intervening solid portions of the shaking ring. When the shaking ring is reversely rotated by an operating arm 17, it is adapted to clean the grate of dust and ashes at the inner and outer edges and also at the openings 15^a. The operating arm, 100 which extends through a slot or opening 18 at the front of the furnace, is preferably provided with an inner threaded terminal 19, which screws into a threaded socket 20, formed in the lug at the front of the shaking ring 11. Any other suitable means, however, may be employed for partially rotating the shaking ring.

In order to enable the shaking ring to be easily vibrated or reversely rotated, it is 110

supported upon steel anti-friction balls 21, operating in arcuate ball races 22 and 23 of the support and the shaking ring. The support is provided at its radially arranged 5 arms with curved lateral extensions 24, projecting from opposite sides of the arms and grooved at their upper faces to form the lower arcuate ball races 22, which are concentric with the center of the grate. The 10 shaking ring is provided in its lower face with arcuate grooves 23, receiving the upper portions of the anti-friction balls, as clearly illustrated in Fig. 7 of the drawings. The curved grooves of the support and the 15 shaking ring permit free movement of the balls, and in order to prevent the grooves from becoming clogged with dust, the support is provided in the bottom of its grooves 22 with slots 26, extending longitudinally 20 of the grooves 22 and curved to conform to the configuration of the same. The slots 26 permit the dust to drop through the lower grooves, and the movement of the anti-friction balls along the grooves will 25 assist in cleaning the same.

The cylinder 16, which constitutes a lining for the fire pot section of the furnace, is provided at its lower edge with recesses 27 forming spaced lower portions, which 30 are located opposite the outer projections 13 of the shaking ring. The fire pot cylinder 16 is supported upon the inwardly extending annular flange 5 of the base 6, and the lower ends of the spaced supporting 35 arms of the cylinder 16 are interposed between the fire pot section of the casing of the furnace and the outer ends of the radial arms 2. The fire pot cylinder may be of any desired height, and the scalloped or recessed lower edge or portion of the same cooperates with the ring 11 in the shaking 40 action thereof.

Mounted upon the central section 1 of the grate is a cone 28, preferably extending upwardly to the plane of the upper edge of the fire pot cylinder 16, but it may be, of course, varied in height and diameter to suit the character of stove or furnace in which it is designed to be used. The cone has a flat 50 base, which fits against the upper face of the central grate section 1, and it is provided with a depending stem 29 extending through a central opening 30 in the grate section 1 and projecting below the same and 55 provided with a slot 31 for the reception of a wedge-shaped key 32, or other suitable means for detachably securing the cone upon the central section of the grate. The upper portion 33 of the stem is threaded and 60 secured in a threaded bore or socket in the center of the base of the cone. The cone 28 may be constructed of a single piece of metal to adapt it for storing up and giving off units of heat, or as illustrated in Fig. 65 6 of the drawings, it may be constructed of

a body portion 34 of fire brick or similar material, having a metallic tip 35 to protect it and prevent it from being injured by the fuel thrown into a stove or furnace. The metallic tip 35, which is conical, is formed 70 integral with and is arranged at the upper end of a rod 36, extending through the body portion 34 of the cone and projecting below the same and provided in its lower depending portion with a slot or opening for the 75 reception of a key 37, or other suitable fastening device for securing the cone to the central section of the grate.

It is a well known fact that the combustion in a stove is the greatest at the center 80 of the fire pot, and as this central heat is not radiated to advantage, but passes off and out through the draft channels to the stove pipe, the greater portion of it is consequently lost. The cone, which fills the 85 central portion of the fire box, is adapted in a great measure to prevent this loss, and when the cone is constructed of heavy cast iron, it is constantly heated by the surrounding fire, and it is heated to such a degree 90 that it throws off the heat units in the center of the fire pot. The cone also distributes the fire in a ring around the fire pot where it impinges against the interior of the stove or furnace casing and where it is adapted to 95 radiate its heat to the greatest advantage. A ring of fire thus maintained in contact with the interior of the furnace casing will be found practically as efficient in the matter of house or building heating as a fire, 100 which completely covers the grate, and the decreased capacity of the fire pot incident to the employment of the cone enables the wall of fire to be maintained at the inner face of the casing at the expenditure of a 105 considerably less amount of fuel than is possible when the fire distributing cone is not employed. The grate is also especially adapted for climates where the temperature or weather is changeable, for when the 110 weather is mild a low fire may be maintained by simply having a ring of fire at the base of the cone, and in extremely cold weather, the fire may be maintained at the height of the top of the cone, which will 115 enable the fire to be easily adjusted or graduated to suit weather conditions.

What is claimed is:—

1. A grate of the class described including a stationary central circular grate section having peripheral projections and provided with outwardly extending supporting arms rigid with the said central grate section, said arms having terminal attaching means for securing them within a stove or 120 furnace for supporting the central circular grate section in a fixed position, and a movable shaking ring supported by the said arms and surrounding the central section in substantially flush relation with the periph- 130

eral projections thereof and provided with means for coacting with the said projections.

2. A grate of the class described including a support consisting of a stationary central circular substantially horizontal grate section having peripheral projections and provided with outwardly extending supporting arms rigid with the central section, said supporting arms being downwardly offset from the plane of the peripheral projections and having means for rigidly securing them within a stove or furnace to support the central grate section in a fixed position, a fire distributing cone seated upon and extending upwardly from the central grate section, and a movable shaking ring supported by the said arms and arranged in substantially flush relation with and surrounding the central grate section and having means for coöperating with the said peripheral projections.

3. A grate of the class described including a cylinder fire pot lining, a fixed support consisting of a circular imperforate grate section provided with peripheral projections, and supporting arms integral with and extending outwardly from the central grate section and provided at their outer ends with attaching means, a solid cone mounted upon the imperforate central grate section and having its base terminating at the projections of the said grate section, and a rotary shaking ring supported by the said arms in substantially flush relation with the central grate section and surrounding the same.

In testimony, that I claim the foregoing as my own, I have hereto affixed my signature in the presence of two witnesses.

VINCENT M. HAAS.
